UNITED STATES PATENT OFFICE

105,575

DESIGN FOR A SEAT COVER

Leo Easterman, Detroit, Mich., assignor to Fry Products, Inc., Detroit, Mich., a corporation of Michigan

Application May 29, 1937, Serial No. 69,617

Term of patent 14 years

To all whom it may concern:

Be it known that I, Leo Easterman, a citizen of the United States, residing at 5910 Audubon Street, city of Detroit, county of Wayne, in the State of Michigan, have invented a new, original, and ornamental Design for a Seat Cover, of which the following is a specification, reference being made to the accompanying drawing, forming part thereof.

Fig. 1 is a front view, in perspective, of a seat cover showing my new design.

Fig. 2 is a rear perspective view thereof.

I claim:

The ornamental design for a seat cover as shown.

LEO EASTERMAN.
